UNITED STATES PATENT OFFICE.

ARTHUR C. ROWLEY, OF PHILADELPHIA, PENNSYLVANIA, ASSIGNOR TO GLOBE AUTOMATIC SPRINKLER COMPANY, OF PHILADELPHIA, PENNSYLVANIA, A CORPORATION OF PENNSYLVANIA.

STRAINER.

Application filed January 12, 1922. Serial No. 528,767.

To all whom it may concern:

Be it known that I, ARTHUR C. ROWLEY, a citizen of the United States, residing in Philadelphia, Pennsylvania, have invented a Strainer, of which the following is a specification.

This invention relates to strainers designed particularly for use in connection with automatic fire extinguishing systems and one object of said invention is to provide a strainer which while capable of functioning in the customary manner to catch and hold solid objects moving in a current of water passing through it, shall be of such construction as to be capable of providing a free passage for water in case its openings become clogged, in order to insure an ample supply of water in case of a heavy or sudden demand such as would be caused by a fire.

A further object of the invention is to provide a strainer which shall include a normally closed valve capable of automatically opening under predetermined conditions to permit unobstructed water flow through the valve even though its perforations or passages should be clogged up.

The invention further contemplates a novel form of strainer element, together with a containing casing so designed as to permit of the convenient insertion and removal of said element; the invention also including relatively simple and substantial means for supporting and holding the strainer element so that it cannot move or get out of adjustment.

It is further desired to provide a strainer particularly designed for use in automatic fire extinguishing systems which shall include a casing for connection in such a system provided with a side opening and a removable strainer element insertible through said opening, together with such an arrangement of parts as shall at all times insure the immovable holding of the strainer element.

These objects and other advantageous ends I attain as hereinafter set forth, reference being had to the accompanying drawings, in which,

Fig. 1 is a side elevation of a strainer

constructed in accordance with my invention and illustrating the removable element in section; and

Fig. 2 is a section taken on the line 2—2,

In the above drawings 1 represents a casing having in the present instance a flanged inlet opening 2, a clean-out opening 3 and a flanged outlet 4 in line with the inlet opening;—the clean-out opening being normally closed by a plate or cover 14. In addition this casing has in one side an elongated, substantially rectangular and suitably flanged opening 5 designed to be normally closed by a plate 6 removably held in position by bolts or other suitable means. The major axis or general line of this side opening 5 is inclined to the line of the two openings 2—4, in the present instance at an angle of about 45°, and within the casing in a plane substantially parallel to that of the major axis of the opening 5 is a seat 7 for the reception of a removable strainer element 8 of such dimensions that it may be inserted in the casing 1 and placed upon said seat through the side opening 5.

Suitable lugs 9 are provided in the casing to cooperate with the seat 7 in providing a guideway for holding the strainer element in place and it is noted that one side of the latter is curved to fit the substantially semi-circular inside wall of the casing 1, opposite which it has a straight edge immediately adjacent and parallel with the cover plate 6 of the side opening 5 so that it cannot shift its position within the casing after said cover plate has once been put in place.

The strainer element itself may be described as having an annular perforated or reticulated body whose central opening is normally closed by a gate or a clapper 10, hinged to what is intended to be the upper side of its body by a pivot pin 11, so that it normally tends to remain upon a seat 12 defining or surrounding the central opening in said strainer element. The gate itself is likewise perforated so that under normal conditions water is free to enter the inlet 2 and pass with but little obstruction from the strainer element to the outlet 4.

Said element however prevents the passage of solid material of such size as cannot pass through its perforations.

- Even though pieces of solid material may lodge against the strainer element and obstruct the effective cross section of the water channel to a greater or less degree, the inclined mounting of said element permits it to have such a relatively large area as compared to either the inlet or the outlet that there is ample opening for the necessary water flow. In the case however of a sudden demand for water, the arrangement is such that if any material clogging of the perforations has occurred, the gate 10 will automatically swing up on its pivot pin and provide an unobstructed opening through the strainer element whose area is substantially equal to that of the inlet or outlet.
- 20 The lower opening 3 is usually normally closed by the plate 14 and an enlargement of the lowest part of the casing constitutes a pocket into which solid material may drop after its passage through the casing has been obstructed by the strainer element. By removal of the plate 14 such material may be removed when desired. The strainer element may be quickly and conveniently removed through the side opening for inspection or cleaning and after being put in place within the casing, can

neither rotate into such position that the valve 10 would automatically tend to open, nor can it in any other way become displaced or out of adjustment.

35

I claim:

1. The combination in a strainer having an inlet and an outlet; a strainer element mounted in the casing in a plane at an angle to the line of flow of liquid from the inlet to the outlet, said element including an annular perforated body; and a gate pivoted to said body in position to normally close the central opening therethrough but free to automatically open to permit passage of material when the perforations of the body become clogged.

2. The combination in a strainer having an inlet and an outlet; a strainer element mounted in the casing in a plane at an angle to the line of flow of liquid from the inlet to the outlet, said element including an annular perforated body having an opening therethrough having substantially the same cross sectional area as that of the outlet; with a gate pivoted at its top to the body and normally closing the opening under the action of gravity, but free to automatically open to permit flow of material when the perforations of said element become obstructed.
